UNITED STATES PATENT OFFICE

RENE SAMUEL, OF PARIS, FRANCE

BUILDING ELEMENT

Application filed February 9, 1928, Serial No. 253,190, and in France February 18, 1927.

The present invention has for its object building elements characterized in that they are in the shape of hollow tetrahedra, having a trihedral right angle. Most generally there are materialized only the faces forming this trihedral right angle, preferably in an open-work form. In these faces there are obtained the passages that are necessary for the means adapted to secure the union of the elements in their different combinations.

The elements obtained in this way are adapted to be fitted one into another for transport, the space occupied by them being then very much reduced.

It is possible to put them together in a large number of different ways, with a view to obtaining the most varied structures.

The accompanying drawings represent by way of example a constructional form of a building element according to the invention and show a certain number of combinations between elements of this type.

Fig. 1 shows one of the elements in perspective.

Fig. 2 shows a series of these elements fitting one into another for the purpose of transport.

Fig. 3 is an end view of a section of a box girder obtained by joining together four elements according to the invention.

Fig. 4 is a corresponding elevation.

Figs. 5 to 8 indicate several modes of arranging the elements in pairs.

Fig. 9 gives an example of using at the same time elements which are multiples of each other.

Figs. 10 to 12 show a certain number of structures that can be erected on the ground.

Figs. 13 and 14 show respectively an element and a combination of element fixed to a ceiling.

Fig. 15 relates to the fixing of elements along a wall.

Figs. 16, 17 and 18 are modifications of Fig. 1.

Each element (Fig. 1) is formed of two panels, 1, 1a, in the form of right-angled triangles, produced by joining bars together.

The two panels 1 and 1a are identical; the large side of their right angle is equal to

double the small side of that triangle. They are put together with their planes perpendicular to each other and are braced at their base by a third panel 2 having the shape of an isosceles right-angled triangle with its right-angled apex truncated. The sides of this angle are appreciably shorter than the sides of the panels 1—1a with which they happen to be assembled.

The elements so formed may be fitted one within another (Fig. 2) and then occupy only a limited space, their transport being thus facilitated.

By putting together four of these elements, as shown in Figs. 3 and 4, a section of a box girder is obtained. The different elements of this section are joined together by small lengths of angle iron, 3, which pass between the panels 1, 1a, and the panel 2. These angle irons project on both sides of the extremities of the section thus serving in addition for joining together adjacent sections whilst contributing to the assembling of the latter.

The successive elements of a structure can be assembled by superposition of their panels 2 (Fig. 8) or by a single side of the right angle of these panels (Fig. 7).

There may also be considered combinations in which two elements are put together by their panels 1 or 1a whether these panels are superposed (Fig. 5) or opposed to each other (Fig. 6).

Instead of having only elements of identical dimensions there may also be employed elements which have dimensions that are multiples of the ordinary panels (4, Fig. 9).

With elements according to the invention it is possible to produce, for example, feet of posts (Fig. 6) by means of four of these elements combined as shown in Fig. 5.

Fig. 11 shows a pylon, the pillar of which is formed by a box girder according to Figs. 3 and 4 carrying from one side to the other of its top a bracket constructed according to Fig. 5.

In similar manner a truss such as that shown in Fig. 12 may be formed.

Other structures may be suspended on a ceiling, as in Figs. 13 and 14.

Brackets may also be formed against a

wall by joining together two elements according to Fig. 5. These elements are applied to the wall either by their panel 2 or by panels 1, 1a.

5 These brackets, instead of being fixed directly to the wall can naturally form part of a more complicated combination fixed to the wall.

10 The building elements can also be formed according to the invention by three angle irons 5, 5' and 5'' assembled perpendicularly to each other, the ends of these pieces of angle iron being joined together by pieces of hoop iron 6, 6', 6''. The latter are in the same 15 plane as the flanges of the angle irons that they join together (Fig. 16).

In the example represented, all the pieces constituting an element are joined together by autogenous welding.

20 In order to obtain a passage for the joining angle iron 3 at the beginning of the angle iron 5, a notch is made at 8 in the bottom of the two angle irons 5', 5''.

25 By making a similar notch in each of the other flanges of the angle irons 5', 5'' (Fig. 17) there is made possible the passage of the joining angle iron 3 in three directions perpendicular to each other; this provides the 30 possibility of new combinations between the building elements according to the invention.

35 The same result may be obtained more simply by beating down at 9 the apex at which the three angle irons 5, 5', 5'' meet, in such a manner as to truncate equally the central edge of all these angle irons.

The angle irons 5, 5' and 5'' are then reinforced about their meeting point, as shown in Fig. 18.

40 The element according to the invention can, by being suitably assembled, permit the erection of entire structures and of houses capable of being taken to pieces, and, when reduced to the necessary extent, they may serve as instructive toys for children.

45 What I claim is:

A building unit comprising three adjacent structural elements at right angles to each other limited by a plane inclined with respect to each of the three concurrent edges of the unit and provided with an aperture extending from the apex of the unit along each of said edges, whereby connecting organs such as angle irons can be inserted in said aperture in any of the three rectangular directions of the edges, and securing means for connecting members.

In testimony whereof I have signed my name to this specification.

RENE SAMUEL.
